UNITED STATES PATENT OFFICE

2,453,926

REVOLUTION COUNTER ACTUATOR

John L. Moody, Oakland, Calif., assignor to
 Friden Calculating Machine Co., Inc., a corporation of California

Application April 21, 1945, Serial No. 589,628

4 Claims. (Cl. 235—103)

1

This invention relates to calculating machines and particularly to the revolutions counter mechanism therefor.

The invention will be disclosed as embodied in a calculating machine of the type disclosed in the patents to Friden, No. 2,229,889, and Number 2,388,209 having a revolutions counter control of the type disclosed in the patent to Friden, No. 2,294,111.

The object of the invention is to provide an improved means for imparting movement to the revolutions counter actuator.

In the drawings:

Figure 1 is a vertical, longitudinal section through the calculating machine showing the revolutions counter and the actuator therefor.

Figure 2 is a vertical, longitudinal section through the portion of the machine in which the improved motion transmitting mechanism for the revolutions counter actuator is located. The section is taken as indicated by the line 2—2 in Figure 4.

Figure 3 is a detail of part of this mechanism. The section is taken as indicated by the line 3—3 in Figure 4.

Figure 4 is a plan view of the mechanism taken as indicated by the line 4—4 in Figure 2.

Figure 5 is a detail view of parts in Figure 4 with the revolutions counter actuator removed.

Figure 6 is a detail view of the motion transmitting cam.

Figure 7 illustrates the driving gear train. The view is taken as indicated by the line 7—7 in Figure 2.

Figure 8 shows a geneva therefor. The view is taken as indicated by the line 8—8 in Figure 2.

Figure 9 shows a sign control mechanism for the revolutions counter.

Figure 10 is a vertical section taken as indicated by the line 10—10 in Figure 9.

As disclosed in the patent to Friden, No. 2,229,889, the keyboard includes numeral keys, one of which is shown at 20 in Figure 1, which may be selectively operated to differentially adjust selector gears 21 on square shaft 22 so that upon rotation of the main drive shaft 23, actuator shafts 24 having actuators 25 thereon will be rotated to turn shaft 22 the differential amount. The rotation of shaft 22 is transmitted through bevel gear 26 or 27 to bevel gear 28 on numeral wheel shaft 29 having numeral wheel 30 thereon. Bevel gears 26 and 27 are interconnected by means of a sleeve 31 which is slidable on the shaft 22. Bail 32 rotatable about a shaft 33 serves to adjust the reversing gear 26, 27 to

2

cause the differential movement of shaft 22 to be transmitted to numeral wheel 30 additively or subtractively.

As explained in detail in the patent to Friden, No. 2,388,209, the revolutions counter comprises a series of numeral wheels 40, each numeral wheel having a gear 41 and a notched disc 42 movable therewith. The numeral wheel actuator comprises an actuator tooth 43 rotatable about the axis of the shaft 44 extending transversely of the machine. Extending parallel with the shaft 33 are two rods 45, 46 which are secured at their ends in plates, one of which is shown at 47 in Figure 1, which plates are secured to the shaft 44. Tooth 43 is urged by a spring 48, secured to the rod 46, in a clockwise direction about the axis of shaft 44, and its motion relative to the plate 47 is limited by the engagement of an arm 49 with rod 45.

10 The actuator tooth 43 is located in the first ordinal position and is adapted to cooperate with whichever gear 41 is opposite thereto, depending on the position of the carriage 39 in which the revolutions counter numeral wheels 40 are located. For every cycle of operation of the drive shaft 23, the tooth 43 has imparted thereto a motion in a substantially rectangular path. This motion is obtained by alternately oscillating and reciprocating the shaft 44. The oscillatory movements of the shaft are utilized to engage the tooth 43 with the gear 41 and to disengage the tooth therefrom while the reciprocatory movements of the shaft are utilized for causing the tooth 43 to rotate the gear 41. In orders 20 other than the first order, similar actuator teeth are provided which are connected by a sleeve to a control arm 50 which cooperates with the notched disc 42 in the next lower order to control transfer operations. Additive or subtractive 25 registration on the revolutions counter is determined by the direction of axial movement of the shaft 44 at the time the tooth 43 is in engagement with the gear 41. The structure so far described is shown in detail in the patent to Friden, No. 2,388,209. However, in the present application the mechanism has a different mode of operation in that the actuator normally occupies a home position situated at a mid point on its rectangular path. Referring to Figure 1, the actuator tooth 43 when at rest in its home position is disposed in the same vertical plane as the axis of the gear 41 and the tooth 43 is disposed opposite the tooth at bottom dead center on the gear 41. As will presently be described, when 30 movement is imparted to the tooth it is first

moved laterally in one direction or the other to dispose it opposite a tooth space in the gear 41 and is then moved into the tooth space to engage the gear after which it moves tangentially with respect to the associated gear 41 to rotate the latter. At the conclusion of this actuation the tooth 43 is withdrawn from the tooth space and finally returned to its original home position. This motion is obtained by oscillating and reciprocating the shaft 44 by means which will now be described in detail. The right end of the shaft 44 (Figure 2) has secured thereto the socket member 51 of a ball and socket joint, ball member 52 of which is secured to a plate 53 attached to an arm 54 which has a slot 55 (Figure 4) at the forward end thereof engaging pivot 56 secured in the frame member 57 so that the arm 54 is adapted to be oscillated about the pivot 56, also to be reciprocated axially of the slot 55. The rear end of the arm 54 has an aperture 58 therein, in which is disposed a cam 60. As shown in Figure 6 the cam is in its full cycle position and, in order to centralize the cam in this position, it has rotatable therewith a centralizer cam 61 having depressions 62, 63 to receive rollers 64, 65 (Figure 5) on arms 66, 67 pivotally mounted at 68, 69 (Figure 4) and interconnected by a spring 70.

Cam 60 is so designed that upon rotation thereof, the ball 52 (Figure 5) will traverse a rectangular path 71. As shown in Figures 4 and 5 the parts occupy their normal position at rest and during each revolution of the cam 60 the ball 52 moves around the path 71 and back to its original position. The direction of travel of the ball along this rectangular path depends upon the direction of rotation of the cam 60. The cam 60 is so contoured that movement of the ball part 52 of the follower 54 will, through its socket connection 51 with the shaft 44, cause alternate reciprocation and oscillation thereof. For example, if the ball 52 traverses its path 71 in a counter-clockwise direction (Fig. 5), the shaft 44 will first be shifted axially to the left, then rocked clockwise (Fig. 2) to engage the actuator tooth 43 with the gear 41, then shifted axially to the right to rotate the gear, then rocked counter-clockwise to withdraw the tooth 43, and finally shifted axially to the left to complete the cycle of movement. Thus, the socket member 51 serves kinematically as a crank arm by which the shaft 44 is oscillated, and serves also to reciprocate the shaft axially.

The means for rotating the cam 60 comprises a shaft 72 (Figure 2) connected by bevel gears 73 to the main drive shaft 23. A mutilated gear 74 (Figures 2 and 7) secured to shaft 72 rotates a pinion 75 on square shaft 76. Geneva wheels 77 (Figure 3) and 78 on shafts 76 and 72, respectively, position and lock the shaft 76 against rotation except during the time the teeth of the mutilated gear 74 are in engagement with the teeth of the pinion 75. The rotation of the shaft 76 (Figure 2) is transmitted to a bevel gear 79 by engaging either of bevel gears 80, 81 therewith. Gears 80 and 81 are interconnected by a sleeve 82 slidable on shaft 76 and adapted to be adjusted by an arm 83 pivoted at 84 and having a flange 85 disposed between the gears 80 and 81. The gear 79 (Figure 3) is secured to the lower end of a shaft 86 suitably supported in the frame and having secured to its upper end the cams 60 and 61. It will therefore be seen that depending upon the adjustment of the arm 83 (Figure 2), cam 60 will be rotated in one direction or

the other to impart movement to the ball 52 in one direction or the other along the path 71 (Figure 5) and through the ball and socket joint 51, 52 (Figure 2), the shaft 44 will be reciprocated and oscillated in order to impart movement along a rectangular path to the actuator teeth.

The control for determining whether the registration in the revolutions counter is to be additive or subtractive is shown in Figures 9 and 10 and corresponds to the construction disclosed in the aforesaid patent to Friden, No. 2,294,111, to which reference is to be had for a detailed explanation thereof. Briefly, the control lever 90 can be adjusted to cause the registration in the revolutions counter to be like or unlike the registration in the accumulator. An arm 91 of the bail 32 (Figure 1) has pivotally connected thereto at 92 (Figure 9), an arm 93 urged counterclockwise by a spring 94 to engage a pin 95 in a notch 96 of a plate 97 secured to a shaft 98. Shaft 98 (Figure 10) has secured thereto an arm 99 carrying a stud 100 which engages in a slot 101 (Figure 2) in the arm 83, so that when the bail 32 is rocked to adjust the reversing gear for the accumulator to determine additive or subtractive registration therein, the arm 91 of the bail through the arm 93 rocks the shaft 98 in one direction or the other to rock the arm 83 (Figure 2) to adjust the reversing gear 80, 81. In this way the reversing gear for the revolutions counter actuator is adjusted when the reversing gear for the accumulator is adjusted, so that the registrations in the revolutions counter are the same in sign as the registrations in the accumulator, that is, they both add or they both subtract.

To obtain registrations of unlike sign in the two registers, the control lever 90 (Figure 9) is pulled forwardly to lift the pin 95 out of the notch 96 and engage the pin 102 on the arm 93 in the notch 103 of the plate 97, so that rocking of the arm 91 will produce rocking of the shaft 98 in the opposite direction so that the reversing gear for the revolutions counter will be adjusted to cause subtractive registration in the revolutions counter when the accumulator reversing gear is adjusted for additive registration, and vice versa.

I claim:

1. In a revolutions counter having a series of numeral wheels, actuating means therefor mounted on a shaft, a mechanism for operating said actuating means by oscillating and reciprocating said shaft comprising a cam, a follower for said cam, a ball secured to said follower and having movement along a substantially rectangular path during each revolution of said cam, a socket secured to said shaft, said ball and socket serving as a motion-transmitting connection between said follower and said shaft, and means to revolve said cam.

2. In a revolutions counter having a series of numeral wheels, actuating means therefor including a shaft having a crank arm, means mounting said shaft for oscillation and for axial reciprocation, and means including a cam device for oscillating said shaft and for reciprocating it axially comprising a single rotatable cam, and a follower for said cam, said cam being contoured so as to transform rotary movement thereof to movement of a part on said follower along a substantially rectangular path during each revolution of said cam, and means operatively connecting said part on said follower to said crank

arm for oscillating said shaft and reciprocating it axially.

3. In a revolutions counter having a series of ordinarily arranged counter wheels mounted for rotation selectively in additive and subtractive directions, actuating means for said wheels including a shaft having a crank arm, means mounting said shaft for oscillation and for axial reciprocation, and means for oscillating said shaft and for reciprocating it axially comprising a cam device including a single reversible rotatable cam, and a follower for said cam, said cam being contoured so as to transform rotary movement thereof to movement of a part on said follower along a substantially rectangular path selectively in opposite directions according to the direction of rotation of said cam, said path being the same for both directions of movement of said part therealong, and means operatively connecting said part on said follower to said crank arm for oscillating said shaft and reciprocating it axially.

4. In a revolutions counter having a series of ordinarily arranged numeral wheels, operating means therefor including a support, an assembly of actuator elements carried by said support and being respectively cooperable with said wheels for rotating the latter, means mounting said support for rocking to move said elements between positions in which said elements are operatively disconnected from said numeral wheels and positions in which said elements are opera-

tively connected to said numeral wheels, said means also mounting said support for movements of said elements substantially perpendicularly to said first-named movements thereof and tangentially to the associated wheels, a cam device including a single rotatable cam and a single cam follower, said cam being contoured so as to transform rotary movement thereof to movement of a part of said follower along a substantially rectangular path during each revolution of said cam, a crank arm on said support, and means operatively coupling said part on said follower to said crank arm for rocking said support and reciprocating it axially.
